UNITED STATES PATENT OFFICE.

ALICE B. SELLERS, OF PITTSBURG, PENNSYLVANIA.

DESIGN FOR A PLATE, &c.

SPECIFICATION forming part of Design No. 25,208, dated March 3, 1896.

Application filed January 16, 1896. Serial No. 575,787. Term of patent 7 years.

To all whom it may concern:

Be it known that I, ALICE B. SELLERS, a resident of Pittsburg, in the county of Allegheny and State of Pennsylvania, have invented a new and original Design for Plates, &c.; and I do hereby declare the following to be a full, clear, and exact description thereof.

My invention relates to designs for plates, saucers, plaques, &c.

10 The accompanying drawing represents a plate with my design applied thereto.

The outer rim of the plate has stars arranged around it at suitable intervals apart.

15 Radiating from the center of the plate are a series of distaffs connected by garlands of flowers. Rosettes are arranged midway between the distaffs.

At the center of the plate is a spinning-wheel with stars around it, forming a circle.

In the drawing, *a* represents the plate, and *b* the stars arranged around its outer rim.

The letter *c* represents the distaffs; *d*, the garlands connecting same; *e*, the rosettes; *f*, the spinning-wheel; *g*, the stars surrounding said wheel, and *h* radially extending lines of balls decreasing gradually in diameter toward the center.

What I claim is—

The design for plates, saucers, plaques, &c., substantially as herein described. 30

In testimony whereof I, the said ALICE B. SELLERS, have hereunto set my hand.

ALICE B. SELLERS.
